US00D545936S

(12) **United States Design Patent** (10) **Patent No.:** **US D545,936 S**
Metaxatos et al. (45) **Date of Patent:** **** Jul. 3, 2007**

(54) **MOSQUITO TRAP DEVICE**

(75) Inventors: **Paul K. Metaxatos**, Swampscott, MA (US); **Kurt M. Maw**, Lexington, MA (US); **Eric Nichols**, Cambridge, MA (US); **E. Cole Nelson, Jr.**, Lakewood, IL (US)

(73) Assignee: **Intermatic Incorporated**, Spring Grove, IL (US)

(**) Term: **14 Years**

(21) Appl. No.: **29/226,639**

(22) Filed: **Mar. 30, 2005**

(51) **LOC (8) Cl.** **22-06**

(52) **U.S. Cl.** **D22/122**

(58) **Field of Classification Search** D22/119-125; 43/107, 112-113, 122, 124, 132.1, 133, 139

See application file for complete search history.

(57) **CLAIM**

The ornamental design for a mosquito trap device, as shown and described.

DESCRIPTION

FIG. 1 is a perspective view of the mosquito trap device showing our new design;

FIG. 2 is a front view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.
